CLOSURE FOR HANDBAGS AND THE LIKE

Elizabeth N. Graham, 834 5th Ave., New York, N.Y.

Filed Aug. 19, 1959, Ser. No. 834,807

5 Claims. (Cl. 150—42)

The present invention relates generally to improvements in receptacle-latching devices, and in particular it relates to a latching mechanism for handbags, pocketbooks, and the like.

The conventional handbag or pocketbook usually includes a bag-opening pair of complementary hinged frame members provided with a snap fastening arrangement to permit the releasable latching of the frame members into a closed position. This type of latching mechanism possesses the disadvantage of not affording a positive opening of the handbag which may be accidentally or surreptitiously opened and the contents of the handbag made fully accessible. There have been devices employed and proposed for effecting a positive locking of the handbag or pocketbook, but these have been generally awkward, inconvenient and unattractive, and have otherwise left much to be desired.

It is thus a principal object of the present invention to provide an improved receptacle latching device.

Another object of the present invention is to provide an improved latching mechanism for handbags, pocketbooks, and the like.

Still another object of the present invention is to provide an improved latching mechanism for handbags and pocketbooks which affords a positive locking of the handbag, and in which accidental opening is highly unlikely.

A further object of the present invention is to provide an improved handbag latching mechanism of the above nature, characterized by its simplicity, ruggedness, low cost and attractive appearance.

The above and other objects of the present invention will become apparent from a reading of the following description, taken in conjunction with the accompanying drawing, wherein

Figure 1 is a top perspective view of a handbag embodying the present invention, illustrated in open position, and partially broken away for convenience of illustration;

Figure 2 is a top plan view of the handbag latching mechanism in closed position, illustrated partially broken away and partially in section;

Figure 3 is a top plan fragmentary view of the latching mechanism during the locking thereof;

Figure 4 is a fragmentary sectional view taken along line 4—4 in Figure 2;

Figure 5 is a sectional view taken along line 5—5 in Figure 2; and

Figure 6 is a fragmentary perspective view of the latching member.

In a sense, the present invention contemplates the provision in a handbag, pocketbook or the like of a pair of hinged first and second complementary frame members relatively movable between a closed and opened position, the frame members including first and second cross bars and end legs depending therefrom and pivoted at their lower termini, channel-shaped first and second track members mounted on said first and second cross bars

2

respectively and disposed in substantially aligned end-to-end arrangement when said frame members are in closed position, with each of said track members including a base web having upstanding side walls provided with inwardly directed legs, and there being an elongated latch member slidably registering with said first track and longitudinally movable therein into locking slidably engagement with said second track to effect a locking of said frame members in closed position, with said latching member having a leading end which is transversely cammed so as to engage the side of said second track adjacent the inner end thereof thereby to urge said tracks into alignment upon movement of said latching member toward locking engagement with said second track.

Referring now to the drawing, which illustrates a preferred embodiment of the present invention, reference numeral 10 generally designates a handbag incorporating the improved latching mechanism and including a frame portion 12 and a receptacle or bag portion 13. Frame portion 12 comprises a hinged pair of first and second inverted U-shaped frame members 14 and 16 respectively, including upper cross-pieces 18 and 20, which are provided with depending side arms 22 connected at their lower ends by headed pivot pins 24. The cross piece and side arm components of each frame member are channel-shaped having outwardly directed legs and inner base portions and are preferably each integrally formed of metal. The frame members 14 and 16 are mutually swingable between a closed position wherein the frame channel base portions are in abutment and an open position wherein the frame members 14 and 16 form a dihedral angle affording an opening for access into the interior of the handbag.

Bag portion 13 may be formed of leather, fabric, plastic or other suitable material, and includes front and rear walls 26 and gusset shaped end walls 28. The side and lower edges of end walls 28 are secured to the side edges of front and rear walls 26, the bottom edges of which are secured to each other. The upper borders of front and rear walls 26 are sandwiched between the channel legs of cross-pieces 18 and 20, and affixed therein, whereas the inner borders of end walls 28 are sandwiched between the channel legs of frame member arms 22 and affixed therein.

In order to releasably latch frame members 14 and 16 in closed position, there are provided a pair of first and second tracks 30 and 32 respectively. Track 30 is mounted on the top face of cross-piece 18 and extends longitudinally from an end thereof approximately two-thirds the length of the cross-piece 18. Track 30 includes a flat bottom web 34 superimposed on the top face of cross-piece 18, and suitably secured thereto, the outer edges of the web 34 approximately coinciding with the outer edge of cross-piece 18 and the web 34 projecting inwardly beyond the cross-piece inner edge a distance approximately equal to the width of the cross-piece 20. Located along the longitudinal edges of web 34 are upright walls 36, terminating in inwardly directed lips 38. Track 32 is similar in configuration to track 30 and extends from the opposite end of the cross-piece 20 approximately one-third the length thereof. The outer edge of the bottom web 34 of track 32 approximately coincides with the corresponding edge of the cross-piece 20, and the web 34 projects inwardly from the cross-piece 20 a distance about equal to the width of the cross-piece 18. Thus, when the frame members 14 and 16 are in closed position, the tracks 30 and 32 are in end-to-end alignment.

A latch member 40 slidably registers with track 30, 70 and comprises an elongated strip 42 including a flat substantially rectangular bottom web 44 having a leading inner corner cut-out as at 46. Projecting from the longi-

tudinal side edges of the web 44 are upstanding parallel walls terminating in inwardly directed lips 50. The strip 42 nests in track 30 and is movable along the length thereof.

A finger piece 52 is formed integrally with the web 44 and projects upwardly from the leading edge thereof. Finger piece 52 includes an upwardly curved base portion 54 extending from the front inner corner 48 of web 44 to a point inwardly of the opposite corner thereof. Projecting inwardly from base portion 54 is a horizontal arm 56 substantially coplanar with lips 38 of track 30 and terminating in an upwardly directed curved finger 58. The inner side edge 60 of arm 56 is outwardly rearwardly inclined from the leading end thereof to a point adjacent the inner edge of the corresponding lips 38 to define a frame-closing cam. The opposite edge of the arm 56 is substantially parallel to lips 38.

A flexible draw-band 63, formed of any suitable material such as leather, plastic, or the like, is superimposed upon the latch member web 44 being suitably secured thereto and having its side borders underlying lips 50. Band 63 projects rearwardly of catch member 40 and terminates in a loop 65 engaging a ring 66 secured to the arm 22 of frame member 14 by means of a second ring 67. A handle 68 of any desired construction is attached to the handbag by means of a pair of metal brackets 70 mounted at opposite ends of the cross-piece 18 and track 30.

The handbag is closed by bringing frame members 14 and 16 into a closely confronting position whereby the tracks 30 and 32 assume the positions illustrated in Figure 3 of the drawing. Latch member 40 is then slid forwardly along track 30 into registry with track 32, the cam defined by the inclined edge 60 engaging the trailing inner corner of lip 38 of track 32. As the latching member 40 is further advanced, the cam surface 60 urges the track 32 into full alignment with the track 30, permitting the sliding of the latch member 40 into full registry with the track 30 thereby to effect the closing and locking of the frame 12 and the handbag 10. In order to permit the opening of the handbag 10, the latch member 40 is merely slid out of registry with the track 32 by manipulation of the finger piece 52 or pulling on the band 63.

While there has been described and illustrated a preferred embodiment of the present invention, it is apparent that numerous alterations, omissions and additions may be made without departing from the spirit thereof.

I claim:

1. In a handbag, pocketbook or the like, a pair of hinged first and second complementary frame members relatively movable between a closed and open position and including first and second cross bars and end legs depending therefrom and pivoted at their lower termini, channel-shaped first and second track members mounted respectively on said first and second cross bars and disposed in substantially aligned end-to-end arrangement when said frame members are in closed position, each of said track members including a base web having upstanding side walls provided with inwardly directed legs, an elongated latch member slidably registering with said first track and longitudinally movable therein into locking slidable engagement with said second track to effect a locking of said frame members in closed position, said latching member having a leading end thereof cammed on one side, said side being adapted to contact the inner side of said second track adjacent the proximate end thereof to urge said tracks into alignment upon movement of said latching member toward locking engagement with said second track.

2. A handbag in accordance with claim 1, wherein said latching member is provided at its leading end with a finger piece having an arm substantially coplanar with said lips of said first track, said arm having a rearwardly outwardly inclined side edge defining said cammed leading end.

3. A handbag in accordance with claim 1, including a flexible band connecting said latching member to a leg of said first frame member.

4. A handbag in accordance with claim 1, wherein said latch member includes a flat bottom web superimposed upon said said first track bottom web, and upstanding side walls terminating in inwardly directed lips.

5. A handbag in accordance with claim 1, wherein said tracks are substantially twice the width of said cross bars and overlie said cross bars when said frame members are in closed position.
